UNITED STATES PATENT OFFICE.

JOHN H. ROBERTSON, OF NEW YORK, N. Y.

MACHINE FOR SCRAPING, SWEEPING, AND SANDING TRACKS.

SPECIFICATION forming part of Letters Patent No. 626,039, dated May 30, 1899.

Application filed March 16, 1897. Serial No. 627,830. (No model.)

To all whom it may concern:

Be it known that I, JOHN H. ROBERTSON, of New York, in the county and State of New York, have invented a new and useful Improvement in Machines for Scraping, Sweeping, and Sanding Tracks, of which the following is a specification.

My invention relates to an improvement in machines for scraping, sweeping, and sanding tracks, and more particularly to means for thoroughly sweeping the track, comprising rotary brushes driven by the advance movements of the machine and guards for receiving the dirt as it is brushed from the track and deflecting it therefrom.

A further object is to provide certain embodiments in the means for bringing the several parts into and out of engagement with the track-rails and also to so construct the machine that it may be used for treating the rails when driven in either direction.

A practical embodiment of my invention is represented in the accompanying drawings, in which—

25 Figure 1 represents a side view, partially in section, of my improved machine. Fig. 2 is a top plan view of the truck and lower portion of the machine. Fig. 3 is a detail view showing the means for raising and lowering the free end of the frame which carries the rotary brush and its driving mechanism. Fig. 4 is a partial top plan view of a portion of the lower part of the machine, showing a modified form of brush-driving mechanism; and 35 Fig. 5 is an enlarged detail cross-section showing the means for guiding the upward and downward movement of the scraper-carrying arm.

In the accompanying drawings I have shown 40 my machine in connection with a suitable supporting-platform mounted upon the axles of two pairs of traction-wheels arranged to travel along the track-rails. The platform is denoted as a whole by A, and it may be made 45 of any desired length and width to suit the purposes to which it is to be used. It is provided with suitable trucks a, by means of which it is supported upon a pair of axles B B', which axles have mounted thereon suitable traction-wheels b. The machine may 50 be provided with any suitable brake mechanism C.

Proceeding to describe the track - rail-scraping mechanism, a suitable rock-shaft D

extends transversely across the machine near 55 its end and is mounted in suitable bearings d, carried by the platform A. This rock-shaft D is provided with a suitable operating-lever d', extending upwardly therefrom through the platform A into a position to be 60 readily grasped by the operator. A scraper-supporting upright E is mounted in the platform A to reciprocate vertically over each of the track-rails, the guides for the said uprights being located near the rock-shaft D. 65 The rock-shaft D is provided with a sector-rack d² opposite each of the scraper-supporting uprights E in position to engage the same, whereby as the shaft D is rocked the said uprights E are positively slid up and down. 70 The upper portion of the upright E, which passes through the upper guide e, is preferably screw-threaded and is provided with a hand-nut e' for positively adjusting the limit of the downward movement of the said upright and also serving to positively hold the said upright away from the track when so desired. The said upright E is permitted a limited lateral movement in its lower guide e² for permitting the scraper which it carries 80 to retain its position within the groove of the rail when the machine is passing around curves in the track.

The scraper is denoted by F, and it is hinged to the upright E, so as to swing upwardly and 85 backwardly, a spring f, extending between an abutment e³ on the upright and the scraper, tending to yieldingly hold the scraper at the limit of its forward movement. The scraper F may be provided with a suitable scraping-point f', which is adapted to enter the groove in the track-rail, which scraping-point is readily renewed. The scraping-point f' may be a portion of a wire cable, if so desired. The rock-shaft-operating lever d' may be provided 90 with a suitable hook d³, which is adapted to be engaged with the dashboard a' when the lever is swung forwardly in position to lift the upright E and the scraper F away from the track. 100

There are two sets of scraper mechanisms, one at each end of the machine, each set consisting of a single rock-shaft and lever, two vertically-reciprocating uprights and scrapers, and two sector-racks for connecting the rock-shaft with the uprights. 105

Proceeding to describe the sweeping mechanism, a rotary brush G is mounted upon

each side of the machine in position to engage a track-rail, the said rotary brush being mounted at or near the free end of a swinging frame H, hinged on the axle B or B' of the running-gear. The rotary brush G is driven in a reverse direction to the direction in which the machine is going by a suitable connection with the axle upon which its supporting-frame is hinged.

10 Proceeding to describe the driving mechanism shown in Fig. 2, the axle g of the brush G has a bevel-gear connection g' with one end of a shaft I, extending along within the frame, the other end of the shaft having a geared connection i with the axle B.

15 The mechanism for driving the rotary brush G (shown in Fig. 4) is as follows: The axle g of the brush G is provided with a suitable sprocket g², which is connected with a sprocket-wheel g³, mounted near the axle B, by a suitable chain g⁴, the axle of the sprocket-wheel g³ being provided with a suitable gear g⁵, intermeshing with a gear b' on the axle B. It will thus be seen that the free end of the frame H may be raised and lowered without interfering with the driving of the rotary brush G when the machine is in motion. The free end of each of the swinging frames H is positively raised and lowered for moving the 25 rotary brushes G away from and into engagement with the track-rail by means of a suitable rod J, having its lower end connected with the free end of the frame H, as at h, preferably by means of a connecting-rod j.

30 35 The upper end of the bar J is screw-threaded, which screw-threaded portion is engaged by a suitable operating hand-wheel K, mounted to rotate in a suitable support k, carried by the platform A, whereby the rotation of the 40 wheel K in one direction will raise the frame H and in the other direction will positively lower the same. These two frames H in the present instance are shown as the one hinged upon one axle B and the other upon the other axle B', the free ends of the said frames being 45 opposite each other, so that the rotary brushes G will engage the track-rails between the wheels b.

50 Proceeding to describe the sanding device, 55 hoppers L are supported by the platform A and are provided with pipes l for directing the sand within the hoppers down onto the track-rails near each of the traction-wheels b. Each of these hoppers L is provided with a suitable valve l', which may be opened and closed mechanically for permitting the sand to escape into the sand-pipe l or to shut off the escape of sand, as is desired. The mechanism shown herein consists of an upwardly-60 extended valve-stem l², which extends up through the top l³ and is there connected to the short arm m of a lever M, pivoted at m'. The long arm m² of the lever being capable of being clamped to a sector m³ by means of 65 a suitable clamping device m⁴, the amount of sand which it may be desired to permit to escape may thus be very accurately deter-

mined by opening and closing the valve l' to the required degree and then clamping the lever M to the sector m³.

70 A guard O is secured to the platform A adjacent to each of the rotary brushes G, the said guard being provided with wings o for receiving the dirt as it is brushed from the track and deflecting it, so that it will fall in 75 a pile along the side of the track. This guard is very desirable where the rotary brushes are mounted to rotate in a line with the track-rail, but would not be used where the brushes rotate at an angle thereto.

80 The operation of my invention is as follows: Supposing that the machine is to be moving in the direction indicated by the arrow upon Fig. 1, the scraping device at the front of the machine is lowered down into engagement 85 with the track-rails, the front sand-hoppers are closed, the rear sand-hoppers are open, and the rear scraping mechanism is raised out of engagement with the track-rails. As the machine is driven the scrapers will effect- 90 ually remove all foreign matter from the rail-grooves. The rotary brushes will then clean off the rails, and the rear sanding device will then sprinkle on the required amount of sand, thus leaving the rails in proper condition for traffic. If the scrapers should strike any obstruction which would tend to break them, they will yield and pass over the same.

95 Because of the limited lateral movement which the scraper is permitted to have its point will not be removed from the groove in the rail when the machine is passed around curves in the track.

100 It will be seen that the pressure of the 105 scraper may be accurately adjusted, the engagement of the rotary brushes with the track may be also accurately adjusted, and the desired amount of sand may be distributed, thereby enabling the machine to accomplish all desired results.

110 It is evident that slight changes may be resorted to in the construction and arrangement of the several parts without departing from the spirit and scope of my invention. Hence I do not wish to limit myself strictly to the 115 structure herein set forth; but

What I claim is—

120 A track-rail-treating machine, comprising a suitable support mounted upon the traction-wheels, rotary brushes mounted in position to engage the track between the traction-wheels, the axis of rotation of the said brushes being at right angles to the track and guards secured to the support adjacent to the rotary brushes, each of the said guards being provided with wings to the front and rear of the 125 rotary brush for receiving the dirt as it is brushed from the track and deflecting it therefrom when the brush is rotated in either direction, substantially as set forth.

JOHN H. ROBERTSON.
